BOILER

Filed April 14, 1930

UNITED STATES PATENT OFFICE

VERLE D. CONKLIN, OF ST. JOSEPH, MICHIGAN, ASSIGNOR TO COMBINATION BOILER CO., OF BENTON HARBOR, MICHIGAN, A CORPORATION OF MICHIGAN

BOILER

Application filed April 14, 1930. Serial No. 444,150.

The invention relates to boilers, and particularly to boilers of the combination fire box and horizontal return tube type, and has for its object to provide a device of this character having a pair of furnaces and adjustable means for controlling the passage of the products of combustion from either or both of said furnaces through the fire tubes in a predetermined oscillating path of travel, said means permitting the path of travel of the products of combustion to be changed as desired in accordance with the type of fuel employed, in accordance with the particular furnace used, or the like.

A further object is to provide a device of this character in which an inner boiler shell is disposed in an outer boiler shell its ends spaced from the ends of the outer shell to provide vertical extensions of the fire box at each end and within the boiler shell per se, and in which vertical extension adjustable baffle plates are disposed whereby said baffle plates may be arranged in combination with the inner and outer shells to form smoke boxes within the outer shell per se, thus eliminating the necessity of providing auxiliary smoke boxes.

A further object is to provide a device of this character in which the fire tubes and smoke boxes are so disposed in the boiler, that, with the use of shiftable baffle members to form the bottom of the smoke boxes, the smoke boxes may be cleaned by shifting the baffle members to dump the soot deposited thereon in use without the necessity of opening the smoke box to remove the soot by hand.

With the above and other objects in view, the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a longitudinal vertical sectional view of the boiler taken on line 1—1 of Figure 2.

Figure 2 is a front view of the boiler show-

ing a part thereof in transverse vertical section on line 2—2 of Figure 1.

Figure 3 is a rear view of the boiler showing a part thereof in transverse vertical section on line 3—3 of Figure 1.

Figure 4 is a fragmentary longitudinal sectional view of the boiler illustrating the use of an oil burner therewith.

Referring to the drawings, which illustrate the preferred embodiment of the invention, the numeral 1 designates an outer boiler shell comprised of a wrapper 25 and front and rear head sheets 26 and 27 respectively, which may be of any desired size and shape. The outer shell 1 is provided with the customary smoke outlet 3, fire door 4, ash door 5, rear access opening 6 and 7, and a door 8 giving access to the inside of the boiler. At the bottom of the outer shell is suitably disposed a grate 9 of any conventional form which preferably extends from the front thereof to a point intermediate thereof at which a suitable transverse bridge wall 10 is disposed. An auxiliary grate (not shown) or a refractory lining 11 suitable for use with an oil burner 12, as shown in Fig. 4, may be disposed between the bridge wall 10 and the rear of the outer shell. Obviously where two grates or furnaces are employed, such as 9 and 11, they communicate with each other above the transverse bridge wall 10.

Within the outer shell 1 is disposed an inner boiler shell 14 comprised of front and rear tube sheets 16 and 28 and fire box crown 15 having side sheets 13 and front and rear door sheets 29 and 30. The inner boiler shell in combination with the outer boiler shell forms the boiler water chambers which extend therebetween, said water chambers including the conventional water legs 2. The tube sheets 16 and 28 are spaced from the front and rear head sheets 29, 30 of the inner shell for purposes to be hereinafter set forth. A plurality of open-ended fire tubes 17 extend horizontally and longitudinally between and through tube sheets 16 and 28 and communicate with the front and rear vertical extensions of the fire box formed respectively between the front tube sheet 16 and front head sheet 29 and between rear tube sheet

28 and rear head sheet 30. Journaled in the inner and outer shells adjacent the front and rear ends thereof and adapted to rotate about their respective axes are a plurality of baffle plates 18, 19, 20 and 21, respectively, which are preferably formed of suitable heat resisting or refractory material. These plates are of a width equal to the spacing of the tube sheets and head sheets of the inner and outer shells between which they are mounted, and when disposed in horizontal position they form closures for the vertical extensions of the fire box hereinbefore described. Suitable locking means (not shown) are provided 10 to hold the baffle plates in desired position, and studs 22 extending from the baffle plates project from the outer shell at one side thereof. A suitable crank 23 fitting said studs is adapted to be employed to rotate said baffle plates from the outside of the boiler as desired without the necessity of working within the boiler to change the position of the baffles as is necessary in boilers of conventional construction. Spacer members 24 encircle the shafts of the baffle plates and extend between the inner and outer shells.

In Figure 1 the baffles 18 and 21 are shown in open or vertical position and baffles 19 and 20 are shown in horizontal closed position. 30 The baffles are disposed in this position when the grate 9 is employed for a coal fire requiring a free passage of large area for the products of combustion, whereby said products of combustion will pass from the grate to the rear of the boiler, thence upwardly past baffle 21, thence into and forwardly through the lower set of fire tubes under the direction of baffle 20, thence upwardly under the direction of closed baffle 19, thence past baffle 18 35 into and rearwardly through the upper set of fire tubes, and thence from said upper set of fire tubes to and through the smoke outlet 13; the afore-described path of travel being clearly illustrated by the arrows in Figure 1. 40 45 When the other furnace 11 is used, as with the oil burner 12 whose products of combustion require a long restricted path of travel, the baffle 21 may be closed, baffle 19 opened, baffle 18 closed, and baffle 20 closed; and the products of combustion will then be directed from furnace 11 to the front of the boiler, thence upwardly past baffle 19, thence into and rearwardly through the lower tubes under the direction of baffle 18, thence upwardly 50 55 into and forwardly through the intermediate tubes below baffle 20 and above baffle 18, thence upwardly into and rearwardly through the upper tubes, and thence out through the smoke outlet 13. It will be seen that the last described path of travel directs the products of combustion four times the length of the boiler to and through the fire tubes, while the first described path of travel directs them to and through the tubes but 60 65 three times the length of the boiler. Ob-

viously more than two baffles may be disposed at each end of the boiler if desired, and by an increased number of baffles a longer path of travel may be had. Both paths of travel direct the products of combustion 70 through all of the tubes, and the changes in the setting of the baffles alter the velocity of the products of combustion from the fire box to the smoke outlet by varying the cross-sectional area of the path of travel by changing the number of tubes in each portion of said path.

It will be observed that the spacing of the tube sheets and head sheets of the inner shell produces several distinct and great advantages as compared with conventional boilers of this type, by virtue of the fact that this construction permits smoke boxes to be formed within the outer boiler shell per se, with the adjacent sections of the inner shell 80 forming the walls of the smoke boxes and the horizontally disposed baffle plates forming the bottoms of the smoke boxes. It is customary in this type of boiler to make the smoke boxes auxiliary to the outer boiler shell 85 because the inner boiler shell conventionally extends substantially the length of the outer shell, but the instant construction eliminates the necessity of such a construction. Material advantages are obtained by this spaced 90 construction, chief among which are the provision of water legs 2 at the end of the boiler where the smoke boxes of conventional boilers are located, thus enlarging the water heating surface of the boiler, providing better 100 water circulation, and increasing the efficiency of the boiler by preventing the loss of heat through the smoke boxes; the compact integral construction of all the elements of the boiler within the outer shell per se; and 105 the ease with which the smoke boxes of this construction may be cleaned, it being necessary only to rotate the horizontal baffles forming the bottoms of the smoke boxes to dump the soot carried thereby into the grates to be 110 reburned or discharged, where as it is necessary with the conventional construction of boiler smoke boxes to provide doors opening into the smoke boxes through which access to the smoke boxes may be had to shovel or 115 otherwise remove the soot by hand with the attendant disagreeable dirt and trouble. Also with this construction in which are provided vertical extensions of the fire box at 120 each end thereof with which adjustable baffle plates are adapted to cooperate, the path of travel of the products of combustion through the boiler may be altered and controlled as desired, thus giving a boiler adaptable for a greater variety of uses and consequently being 125 much more flexible than conventional boilers of this type.

By the use of the double furnace construction many advantages and possible combinations may be obtained. Thus the furnaces 130

may be arranged with a grate and a gas or oil burner to permit the use of gas or oil as the heating fuel and to provide for means with which coal or other solid fuel may be employed for auxiliary heating purposes; or to permit the grate to be used as a garbage incinerator. Another combination which might be used is the combination of two grates, one for heating purposes and the other as a garbage incinerator.

Thus this construction has the advantages of being easily adaptable for many different uses at small expense; of having baffles easily adjustable from the exterior of the boiler and adapted to direct the products of combustion in any desired path of travel through the boiler, and of having smoke boxes integrally formed within the boiler shell per se and arranged to be easily cleaned from the exterior of the boiler without the necessity of opening and reaching into the same.

The invention having been set forth, what is claimed as new and useful is:

1. In a boiler of the combination fire box and return tube type, the combination of an outer boiler shell having a smoke outlet and a double furnace forming a fire box, an inner shell disposed in said outer shell, the front and rear ends of said inner shell being spaced from the ends of the outer shell, to form water legs, tube sheets carried by said inner shell in spaced relation to the ends of said inner shell, the space between said tube sheets and the ends of said inner shell forming vertical extensions of the fire box, a plurality of open ended horizontal tubes carried by said tube sheets and a plurality of spaced baffle plates rotatably mounted in the vertical extension of the fire box, said baffle plates being adjustable to direct the products of combustion in predetermined paths of travel through the fire tubes from the furnace in use to the smoke outlet.

2. In a boiler of the combination fire box and return tube type, the combination of an outer boiler shell having a smoke outlet and a fire box, an inner shell disposed in said outer shell, means carried by said inner shell and cooperating with the ends of said outer shell to form end water legs in spaced relation to the ends of said inner shell, a plurality of horizontal fire tubes passing longitudinally through said inner shell, and a plurality of spaced baffle plates adjustably mounted between the ends of said inner shell and said end water legs.

3. In a boiler of the combination fire box and return tube type, the combination of an outer boiler shell having a smoke outlet and a fire box, an inner shell disposed in said outer shell in spaced relation thereto, means cooperating with the ends of said outer shell to form end water legs spaced from the ends of said inner shell, a plurality of horizontal fire tubes passing longitudinally through said inner shell and communicating with said fire

box, and adjustable means for directing the products of combustion through said fire tubes in predetermined paths of travel from the fire box to the smoke outlet.

4. In a boiler, the combination of an outer boiler shell having a smoke outlet and a fire box, an inner shell disposed in said outer shell in spaced relation thereto, tube sheets spaced from the ends of said inner shell, a plurality of fire tubes extending through said tube sheets and communicating with said fire box, and a plurality of spaced baffle plates rotatably mounted between said tube sheets and the ends of said inner shell to adjustably direct the path of travel of the products of combustion through said tubes.

5. In a boiler, the combination of an outer boiler shell having a smoke outlet and a fire box, an inner shell disposed in said outer shell having end plates spaced from the ends of said outer shell and tube sheets spaced from said end plates, the spaces between said end plates and tube sheets forming vertical extensions of the fire box, a plurality of fire tubes carried by said tube sheets passing through said inner shell and communicating with the vertical extensions of said fire box, and adjustable baffle plates disposed in the vertical extensions of said fire box to direct the path of travel of the products of combustion through said fire tubes.

6. In a water jacketed boiler, the combination of an outer boiler shell having a smoke outlet and a fire box, an inner shell disposed in said outer shell, a plurality of fire tubes passing through said inner shell and communicating with said fire box with said outer shell, and adjustable means for directing the products of combustion through said fire tubes in variable predetermined paths of travel of variable cross sectional area.

7. In a boiler of the combined fire box and return tube type, the combination of an outer boiler shell having a smoke outlet and a fire box, said fire box comprising spaced furnaces, an inner shell mounted in said outer shell with its ends spaced from the ends of said outer shell to form water legs, a plurality of fire tubes passing longitudinally through said inner shell and communicating with said fire box, and a plurality of spaced baffle plates rotatably mounted adjacent the ends of said fire tubes and adapted to be positioned to direct the products of combustion of either furnace in a predetermined path of travel through said fire tubes to said smoke outlet.

8. In a boiler of the combined fire box and return tube type, the combination of an outer boiler shell having a smoke outlet and a fire box, spaced furnaces communicating with said fire box, an inner shell mounted in said casing with its ends spaced from the ends of the outer shell to form water legs, a plurality of fire tubes passing longitudinally

through said inner shell and communicating with said fire box, and a plurality of spaced adjustable baffle plates mounted adjacent the ends of said fire tubes, said baffles being adapted to be positioned with respect to said shells to form smoke boxes within the boiler.

9. In a boiler of the combined fire box and return tube type, the combination of an outer boiler shell having a smoke outlet and a fire box, spaced furnaces communicating with said fire box, an inner shell mounted in said outer shell with its ends spaced from the ends of said outer shell to form water legs, tube sheets carried by said inner shell in spaced relation to the ends of said inner shell, a plurality of fire tubes carried by said tube sheets passing through said inner shell and communicating with said fire box, and means for adjustably directing the path of travel of the products of combustion from said fire box through said fire tubes to accommodate the use of either furnace.

10. In a boiler of the combination fire box and return tube type, the combination with a water jacketed boiler shell having a smoke outlet and a fire box, said fire box comprising a double furnace, of a plurality of open ended fire tubes disposed in said shell with their ends spaced from the end walls of said shell to provide vertical extensions of the fire box between said shell and tubes at each end of the shell, and adjustable baffles interposed between said shell and tubes to direct the products of combustion from said fire box to said smoke outlets in predetermined paths of travel.

In testimony whereof I affix my signature.

VERLE D. CONKLIN.
